US0D1029793S

(12) **United States Design Patent** (10) **Patent No.:** **US D1,029,793 S**
Ho (45) **Date of Patent:** **** Jun. 4, 2024**

(54) **ROTATABLE BONE CONDUCTION
HEADSET**

(71) Applicant: **DONGGUAN PURE AUDIO
TECHNOLOGY CO., LTD.,**
Dongguan (CN)

(72) Inventor: **Chunchun Ho**, Guangdong (CN)

(73) Assignee: **Dongguan Pure Audio Technology
Co., Ltd.**, Dongguan (CN)

(**) Term: **15 Years**

(21) Appl. No.: **35/517,508**

(22) Filed: **Dec. 10, 2022**

(80) **Hague Agreement Data**

Int. Filing Date: **Dec. 10, 2022**

Int. Reg. No.: **DM/226755**

Int. Reg. Date: **Dec. 10, 2022**

Int. Reg. Pub. Date: **Jun. 16, 2023**

(30) **Foreign Application Priority Data**

Nov. 4, 2022 (CN) 202230735900.6

(51) **LOC (14) Cl.** **14-01**

(52) **U.S. Cl.**

(57) **CLAIM**

The ornamental design for a rotatable bone conduction headset, as shown and described.

DESCRIPTION

1. Rotatable bone conduction headset
2. Rotatable bone conduction headset
3. Rotatable bone conduction headset

1.1 : Front Perspective

1.2 : Rear Perspective

1.3 : Front

1.4 : Back

1.5 : Left

1.6 : Right

1.7 : Top

1.8 : Bottom

2.1 : Front Perspective

2.2 : Rear Perspective

2.3 : Front

2.4 : Back

2.5 : Left

2.6 : Right

2.7 : Top

2.8 : Bottom

3.1 : Front Perspective

3.2 : Rear Perspective

3.3 : Front

3.4 : Back

3.5 : Left

3.6 : Right

3.7 : Top

3.8 : Bottom

(Continued)

The broken lines in the drawings depict portions of the rotatable bone conduction headset that form no part of the claimed design.

1 Claim, 24 Drawing Sheets
